UNITED STATES PATENT OFFICE

2,599,747

SLIDING DOOR MOUNTING DEVICE

Adam Craigan, Toronto, Ontario, Canada, assignor to Margison and Babcock, Toronto, Ontario, Canada

Application May 18, 1949, Serial No. 93,863
In Canada May 3, 1949

7 Claims. (Cl. 20—19)

1

This invention relates generally to a mounting device for sliding doors and more particularly to doors adapted for use in aircraft hangars where large heavy panels must be moved to accommodate passage of large aircraft.

It is a principal object of the invention to provide means for shielding the moving parts of the door mounting from dirt, rain, snow and the like.

It is also a principal object of the invention to provide a sliding door which will function efficiently throughout the extremes of weather conditions encountered in, say, the North American continent.

It is a further object of the invention to provide means whereby a door panel may be moved by equal forces applied along opposed edges of the panel, thus avoiding the tendency to binding which is associated with the acceleration and deceleration of heavy doors which are driven by a force applied along one edge only.

Further objects of the invention are the provision of heating means and blow-out means associated with the means for supporting and driving the door panel.

With these and other objects in view my invention generally comprises a mounting device for a sliding door which includes in combination, at least one panel, a housing having a longitudinally extending slot, supporting means within the housing and slidable in parallel relation to said slot, means disposed between the supporting means and the slot for occluding dirt and ice, snow, rain and the like, from the interior of the housing, and web means extending from the supporting means through the occluding means and the slot to mount said door panel.

Other objects of the invention will be apparent after a study of the following detailed specification and the accompanying drawings.

In the drawings,

Figure 1 is a diagrammatic representation of the invention in its broadest aspect.

Figure 2 is an elevational view of a vertically disposed door panel mounted above and below in accordance with one modification of my invention.

Figure 3 is a partial elevational view on an enlarged scale of the lower mounting of one of the panels shown in Figure 2.

Figure 4 is a cross sectional view on an enlarged scale taken along the line 4—4 of Figure 2.

Figure 5 is an enlarged cross sectional view taken along the line 5—5 of Figure 2.

Figures 6, 7, 8 and 9 are modifications of the 55 idler sprocket, the other sprocket (25) a driven

2

invention which schematically show a group of door panels mounted according to the invention in several different arrangements which serve to open or close wide doorways.

5 In Figure 1, which has been provided to show the broadest aspect of the invention, reference character A represents an edge portion of a door panel; B represents a housing having a longitudinally extending slot C; D a support means slidable within housing B; E a carrier rigidly secured to support means B and to panel portion A; and F represents an occluding means mounted upon carrier E adjacent slot C. Occlusive means F, support means D, and carrier E have been shown 10 as secured in unit form by means of rivets G. Nut and bolt means H have been shown as securing the carrier E to the panel portion A. It will be apparent that many forms of securement could be substituted both for rivets G and nut and bolt means H. Occluding means F may take the form of a flexible belt, and this flexible belt may additionally function as a drive means whereby the supporting means may be slid within the housing B and the door panel moved in parallel 15 relation to the slot C. Occluding means F should be substantially twice as long as the panel, in order that it may be employed to block the slot C when the panel has been withdrawn from the normal closed position.

20 Referring to Figures 2 to 5 reference numeral 10 represents a door panel which is slidably mounted in an upper housing 11 and a lower housing 12. Each housing consists essentially of two parallel spaced apart channel members 13 set apart by means of an I-beam 14. Sections of weatherstripping 15 are mounted at each side of channel members 13, leaving a slot 15a therebetween. Slot 15a extends longitudinally along 25 housings 11 and 12. A track 16 is rigidly secured by welding as at 17 to the bases of the channel members 13 adjacent the upper and lower edges of the panel 10. The opposed upper and lower edges of panel 10 are slidably mounted on tracks 16 by means of a series of bracket members 18, each of the brackets having a web means 19 extending therefrom and rigidly secured to panel 10 by nut and bolt means 20 and a pair of arms 21 extending from the bracket 18 on the side remote from the web means. A flanged carriage 30 wheel 22 is rotatably mounted between said arms by means of an axle 23. Carriage wheels 22 ride upon tracks 16.

At opposed ends of upper housing 11 sprockets are mounted. One of these sprockets (24) is an

3

sprocket. An idler sprocket 26 and a driven sprocket 27 are similarly disposed in lower housings 12. A link chain 28 is mounted upon sprockets 24 and 25 and a link chain 29 is mounted upon sprockets 26 and 27. Alternate links 30 of link chain 29 are secured over a portion of the length of this chain to the sides of brackets 18 remote from web means 19. Flexible occlusive belts 28a and 29a are exteriorly mounted upon link chains 28 and 29 respectively. Where the link chains 28 and 29 are secured to the brackets 18, the occlusive belts rest upon the sides of the brackets 18 from which the web means 19 extend, and the belts are slotted for the passage of the web means therethrough.

Web means 19 are secured to the lower edge of the door panel in the following manner. The edge 31 of the panel 10 is constructed of wood which is slotted centrally and longitudinally as at 32. A U-shaped channel member 33 is secured to wooden edge 31 by screws 34. Channel member 33 has a slot 35 which is aligned with slot 32. Two substantially L-shaped members 36 are rigidly secured to channel member 33 by bolts 37. The space between the two L-shaped members 36 constitutes a slot which is a continuation of slots 32 and 35. Web means 19 extends within these slots. Rubber weatherstripping 38 is exteriorly mounted on L-shaped members 36, and the web means 19, L-shaped members 36, and weatherstripping 38, are drawn together by nut and bolt means 20, in which the bolt passes through the several elements. The web means 19 is secured to the upper edge of the door in the same manner, with the exception that where the bolt passes through the web means, an elongated vertical slot 39a is provided in the web means to facilitate any vertical adjustment of the web relative to panel necessitated by building truss sag or deflection.

A motorized gear speed reducer 40 is rigidly mounted within the hangar adjacent the edge of the doorway. A rotating shaft 41, having a bevel gear 42, drives aligned shafts 43 and 44 through bevel gears 45 and 46 respectively. Gears 47 and 48 on shafts 43 and 44 respectively drive sprockets 25 and 27 respectively. The gearing is so arranged that link chains 28 and 29 are given similar linear velocities whereby chains 28 and 29 drive the door panel from above and below with equal force.

Within the channel members 13, perforated tubes 49 are mounted, preferably by welding. These tubes 49 may be manifolded outside the housings whereby high pressure steam, compressed air, anti-freeze fluids, and lubricant may be blown through the perforations onto the elements within the housings, either to remove dirt therefrom or to enable them to function at low temperatures.

Heating tubes 49a are mounted in conjunction with the channels 13. Tubes 49a are preferably radiant heating tubes, but might of course be any other conventional heating tube, e. g. air. The provision of tubes 49a enables the door of my invention to be effectively employed in northern latitudes.

Figure 6 schematically shows a sliding door in which six door panels 50 are mounted according to the invention. Each panel 50 is slidably mounted in upper and lower slotted housings which extend between and terminate within pockets 51 and 52 at each side of the doorway. Driven sprockets or sheaves 53 are rotatably mounted at one side of the doorway and idler

4
sprockets or sheaves 54 are rotatably mounted at the other side of the doorway. A flexible drive means 55 is mounted upon an aligned pair of sprockets or sheaves 53 and 54, and is disposed within each housing. Each of the flexible drive means 55, in the lower housings, is secured to the bottom of a panel 50, and each of those in the upper housings is secured to the top of a panel 50. With this arrangement any panel 50 may be withdrawn into either pocket 51 or pocket 52, or driven to any desired intermediate position.

Figure 7 schematically illustrates a sliding door in which six panels 56 are mounted according to the invention. The central panels abut one another. The panels to the right of centre are slidably mounted in three upper and three lower slotted housings which terminate within a pocket 57. Of the three sets of upper and lower housings; the first extends outwardly from the pocket substantially one door width; the second, two door widths; and the third, three door widths. Driven sprockets or sheaves 58 and idler sprockets or sheaves 59 are rotatably mounted at opposite ends of the housings. A flexible drive means 60 is mounted upon an aligned pair of sprockets or sheaves 58 and 59 and disposed within each housing. Flexible drive means 60 are secured to panels 56 in the same manner as described in connection with drive means 55 and panels 50. The structure on the left of the centre line is identical to that on the right, and the elements corresponding to elements 57, 58, 59 and 60 have been numbered 57a, 58a, 59a and 60a, respectively, in the drawing.

Figure 8 schematically illustrates a sliding door having six panels 61 mounted in accordance with the invention. This particular arrangement differs from that described in connection with Figure 7, in that centrally disposed idlers 62 and 62a are employed in place of idlers 59 and 59a.

It will be appreciated that by controlling the linear velocities of the flexible drive means in Figure 7 and Figure 8, the panels 56 and 61 may be driven individually, or in unison at uniform speed, or at a three-gang differential speed which would bring about simultaneous pocketing of the panels.

Figure 9 schematically illustrates an arrangement which is generally similar to that of Figure 8, with the exception that five panels 63 are employed in place of the six panels 61, and the central member of the group of five panels 63 is mounted so as to take up any position from the extreme of pocket 57 to the extreme of pocket 57a. With this arrangement, either outermost sprocket 58 or 58a would be an idler sprocket.

I prefer to provide bumpers to limit the run of each door panel and, where an electrical power source is employed to actuate the drive means, conventional limit switches may also be employed to limit the run of a panel.

I also prefer to employ, in conjunction with each door panel, an automatic brake. An example of a suitable brake which could be employed when the drive is electrical would be a solenoid operated device which would be in an inoperative position as long as current was being supplied to the electric motor, and is urged into an operative position by a suitable spring whenever the solenoid is de-energized by the cessation of current flow to the electric motor.

While certain embodiments of the invention have been disclosed, it is to be understood that

70
75
76

the invention may be carried out in a number of ways. This application is not to be limited by the precise details described, but is intended to cover all variations and modifications thereof falling within the spirit of the invention or the scope of the appended claims.

What I claim as my invention is:

1. A mounting device for a sliding door panel and comprising in combination: a housing having co-planar spaced apart flanges forming a longitudinally extending slot therebetween; supporting means within the housing and slidable in parallel relation to said slot; occluding means disposed between the supporting means and the slot and slidably engaging surfaces of said flanges, being in the form of a flexible belt which additionally functions as a means whereby the supporting means in the door panel may be moved; and web means extending from the support means through the occluding means and the slot to mount said door panel.

2. A door panel mounting device, comprising in combination: a housing having co-planar spaced apart flanges forming a longitudinally extending slot therebetween; supporting means within the housing and slidable in parallel relation to said slot; means disposed between the supporting means and the slot and slidably engaging surfaces of said flanges for occluding dirt, ice, snow, rain, and the like from the interior of the housing; web means extending from the supporting means through the occluding means and the slot to mount said door panel; a driven sprocket and an idler sprocket mounted within said housing; and a flexible chain mounted upon said sprockets, said flexible chain being secured to said occluding means and to said supporting means whereby said door panel is driven in parallel relationship to said slot as said driven sprocket is rotated.

3. A door panel mounting device comprising in combination: a housing having co-planar spaced apart flanges forming a longitudinally extending slot therebetween; supporting means including brackets disposed within the housing and slidable in parallel relation to said slot; a series of wheels rotatably mounted in said brackets; means disposed between the supporting means and the slot and slidably engaging surfaces of said flanges for occluding dirt, ice, snow, rain, and the like from the interior of the housing; means securing said occluding means to said brackets on the side remote from said walls; web means extending from the supporting means through the occluding means and the slot to mount said door panel; and slots in said occluding means adapted for the passage of said web means therethrough.

4. A door panel mounting device comprising in combination: a housing having co-planar spaced apart flanges forming a longitudinally extending slot therebetween; supporting means including brackets disposed within the housing and slid able in parallel relation to said slot; a series of wheels rotatably mounted in said brackets; means disposed between the supporting means and the

slot and slidably engaging surfaces of said flanges for occluding dirt, ice, snow, rain, and the like from the interior of the housing; means securing said occluding means to said brackets on the side remote from said walls; web means extending from the supporting means through the occluding means and the slot to mount said door panel; slots in said occluding means adapted for the passage of said web means therethrough; and a track rigidly mounted in said housing in parallel spaced apart relationship to said slot, said wheels riding on said track.

5. A door panel mounting device, comprising in combination: a housing having co-planar spaced apart flanges forming a longitudinally extending slot therebetween; supporting means within the housing and slidable in parallel relation to said slot; means disposed between the supporting means and the slot and slidably engaging surfaces of said flanges for occluding dirt, ice, snow, rain, and the like from the interior of the housing; web means extending from the supporting means through the occluding means and the slot to mount said door panel; and perforated blowout tubes disposed within said housing.

6. A door panel mounting device, comprising in combination: a housing having co-planar spaced apart flanges forming a longitudinally extending slot therebetween; supporting means within the housing and slidable in parallel relation to said slot; means disposed between the supporting means and the slot and slidably engaging surfaces of said flanges for occluding dirt, ice, snow, rain, and the like from the interior of the housing; web means extending from the supporting means through the occluding means and the slot to mount said door panel; and heating tubes mounted in conjunction with said housing.

7. A door panel mounting device comprising the combination of: at least one panel, two housings, a longitudinally extending slot in each of said housings, supporting means within each of said housings, said supporting means being slid able in parallel relation to said slots, means in the form of flexible belts disposed between said supporting means and said slots for occluding dirt, ice, snow, rain, and the like from the interiors of said housings, and web means extending from each of the supporting means through the adjacent flexible belt and slot to mount an opposed edge of said door panel.
